(57) **CLAIM**

The ornamental design for a handle for a tugging cart, as shown and described.

DESCRIPTION

FIG. 1 is an isometric view for a handle for a tugging cart in accordance with the present invention;

FIG. 2 is a front elevational view of the handle of FIG. 1; FIG. 3 is a side elevational view of the handle of FIG. 1; FIG. 4 is a rear elevational view of the handle of FIG. 1; FIG. 5 is a top plan view of the handle of FIG. 1; and, FIG. 6 is a bottom plan view of the handle of FIG. 1. The broken line shown in FIGS. 1, 2, 3, 5 and 6 is to show indefinite length.
